CORE DRILL

John H. Howard, Huntington Park, and Alfred C. Catland, Alhambra, Calif.; said Catland assignor to Globe Oil Tools Company, Los Nietos, Calif., a corporation of California

Application February 19, 1935, Serial No. 7,208

9 Claims. (Cl. 255—72)

The invention relates to a well drilling tool and relates more particularly to a well core drill. A general object of this invention is to provide a practical efficient core drill having improved core recovering means or core catching means.

Another object of the invention is to provide a core drill embodying a novel combination of core catchers or core catching units that are operable to recover cores of any character of earth formation that may be encountered in the drilling of wells. The drill of the present invention is operable to recover cores of very hard earth formation, cores of soft earth formation, undersized cores and broken or shattered cores.

Another object of the invention is to provide a core drill that includes a slip type core catcher operable to break hard solid cores free from the formation and to retain such cores, and a pivoted dog type catcher operable to recover and retain soft cores, undersized cores and broken cores whereby the drill is operable to recover all classes of cores.

Another object of the invention is to provide a core drill of the character mentioned in which the provision of the two core catching units does not make the drill bulky or materially complicate its construction.

A further object of the invention is to provide a core drill of the character mentioned that includes tubular dummies adapted to occupy the spaces normally occupied by the core catchers whereby the drill may be operated using only one core catcher without danger of the core fouling the shoulder in the upper end of the space intended for the core catcher that is not in use.

The various objects and features of our invention will be fully understood from the following detailed description of a typical preferred form and application of our invention, throughout which description reference is made to the accompanying drawing, in which:

Fig. 1 is a central longitudinal detailed sectional view of the principal lower end portion of the drill provided by this invention in operation in a well bore. Fig. 2 is an enlarged top or plan view of the dog type core catcher with a portion in transverse cross section, being a view taken as indicated by line 2—2 on Fig. 3. Fig. 3 is a side elevation of the dog type catcher with a portion in vertical cross section. Fig. 4 is an enlarged side elevation of the slip type core catcher showing a portion in vertical cross section. Fig. 5 is a bottom end view of the slip type core catcher. Fig. 6 is an enlarged side elevation of the dummy for replacing the slip type catcher with a portion

in longitudinal cross section, and Fig. 7 is an enlarged side elevation of the dummy for replacing the dog type catcher showing a portion in vertical cross section.

The core drill of this invention includes, generally, a tubular body 10, a cutting head 11 on the lower end of the body 10, a core catching unit 12 in the head 11 and a core catching unit 13 in the body 10.

In the type of drill illustrated the body 10 comprises the outer barrel and is adapted to be connected with the operating string or drilling string. The body 10 may be made up of as many tubular parts or sections as required. The portion of the body 10 illustrated in the drawing includes a connecting member or sub 14 having a threaded pin 15 on its lower end. A tubular member or sub 16 is threaded on the pin 15 to constitute the lower end member of the body 10. A threaded pin 17 is provided on the lower end of the sub 16 for carrying the cutting head 11. An inner barrel 18 is provided for receiving the core C. The inner barrel 18 is a thin walled tubular member having a thickened collar 19 welded on its lower end. The collar 19 is rotatable in the sub 16 to rotatably support and guide the lower end of the inner barrel 18. The upper portion 20 of the longitudinal opening 21 extending through the sub 16 is enlarged and its lower wall forms an upwardly facing annular shoulder 22. The collar 19 is received in the enlargement 20 of the sub opening 21 and its lower end is adapted to cooperate with or rest on the shoulder 22. The collar 19 continues upwardly into the pin 15 and carries a hardened bearing 23 for cooperating with the lower end of the pin 15. During drilling when the core C engages the interior wall of the inner barrel 18 and tends to hold the inner barrel stationary the bearing 23 cooperates with the lower end of the pin 15.

The inner barrel 18 is spaced from the interior of the body sub 14 leaving an annular fluid passage 24. An annular recess 25 is provided in the wall of the lower sub 16 and ports 26 are provided in the collar 19 to put the passage 24 in communication with the recess 25. Spaced longitudinal ports 27 are provided in the wall of the sub 16 and extend downwardly from the recess 25 to carry the circulation fluid to the cutting head 11.

The cutting head 11 includes a tubular body or shoe 28. The shoe 28 has a threaded socket 29 in its upper end receiving the pin 17. The upper end of the shoe 28 may be flat to bear against the lower end of the sub 16. The socket continues downwardly below the lower end of the pin 17 so

that the lower end of the pin forms a downwardly facing annular shoulder 30. The open lower portion of the socket 29 is plain or unthreaded. The longitudinal or vertical opening 31 in the shoe 28 receives the core C as it is formed and is concentric with the inner barrel 18 so that the core is adapted to project upwardly into the inner barrel.

The shoe 28 carries cutting parts or cutting means for making an annular cut in the earth formation and for forming the core C. In the particular case illustrated the cutting means includes roller cutters A and B. The cutters A and B are rotatably mounted in recesses 32 in the lower end of the shoe 28. Pins 33 extend through the recesses 32 and carry bushings 34 and bearings 35 for rotatably supporting the cutters A and B. The cutters A which are the inner cutters are substantially cylindrical and project downwardly and inwardly from the recesses 32 to cut the inner portion of the bore and trim the core C. The cutters A are rotatable about axes inclined downwardly and outwardly relative to the longitudinal axis of the drill. The outer cutters B are substantially frusto-conical and are rotatable about downwardly and inwardly inclined axes. The cutters B project from the lower end of the shoe 28 and beyond the periphery of the shoe to cut the bore to size. An annular groove 36 is provided in the upper end of the shoe 28 to communicate with the lower ends of the ports 27. Ports 37 are provided in the wall of the shoe 28 and extend downwardly from the groove 36 to the recesses 32 to discharge the circulation fluid against the cutters A and B.

The core catching unit 12 in the cutting head 11 is operable to retain cores of various characters but is particularly adapted to recover cores of medium hard formation, relatively soft earth formation, undersized cores and shattered cores. The unit 12 includes an annular body or ring 38 arranged in the lower end of the socket 29 between the bottom wall of the socket and shoulder 30. The ring 38 is sectional comprising two sections 39 arranged one within the other. The outer section 39 surrounds the upper portion of the inner section 39 so that the exterior of the ring 38 is stepped or of two diameters. Registering annular grooves are provided in the opposing surfaces of the ring sections 39 to form an annular groove or opening 40. Circumferentially spaced openings 41 are provided in the wall of the ring 38 to intersect the opening 40. The openings 41 have extensions or continuations 42 extending upwardly in the inner side of the ring to its upper end. The ring 38 is proportioned to be freely rotatable in the socket 29 so that it is free to float and remain stationary when the drill is rotating during the drilling operation. The ring 38 also has limited longitudinal movement in the socket 29.

The core recovering unit 12 includes core engaging and gripping members in the form of pivoted dogs 43 and 44. The dogs 43 and 44 are pivotally supported in the openings 41 to project from the inner side of the ring 38. Pivot pins 45 extend through transverse openings in the dogs 43 and 44 and the opposite end portions of the pins are received in the opening 40. The pins 45 support the dogs 43 and 44 for pivotal movement between upright inactive positions in the openings 42 and projecting substantially horizontal positions such as illustrated in Figs. 1, 2 and 3 of the drawing. The projecting end portions of the pins 45 are flat or faced off to engage the

wall of the opening 40 for the purpose of holding the pins against rotation and longitudinal movement. The inward or downward pivoting of the dogs 43 and 44 is limited by the lower faces of the dogs cooperating with the bottom walls of the openings 41. The upper and lower faces of the dogs 43 and 44 converge outwardly to comparatively sharp edges for biting into the core C.

In accordance with the invention the dogs 43 are comparatively long to project a substantial distance into the interior of the ring 38 when fully actuated. The dogs 44 may be comparatively short. There may be any desired number of core recovering dogs 43 and 44. In the particular case illustrated there are four circumferentially spaced dogs 43 and four dogs 44 spaced between the dogs 43. The spaced long dogs 43 are effective in recovering and retaining soft cores, undersized cores and shattered cores. The shorter dogs 44 are effective in recovering and retaining medium hard cores, medium soft cores and full sized cores. Spring means are provided for urging the dogs 43 and 44 into cooperation with the core C. Cuts or slots 46 are provided in the pivoted end portions of the dogs 43 and 44 and torsional springs 47 are arranged in the slots 46 to surround the pivot pins 45. The springs 47 each have an end acting against the ring 38 and an end acting against a dog so that the springs urge the dogs downwardly and inwardly to engage the core.

The invention includes cam means for positively pivoting the dogs 43 and 44 inwardly to cooperate with the core C when the drill is raised to recover the core. A downwardly inclined cam shoulder 48 is provided on the wall of the socket 29. The projecting outer ends of the dogs 43 and 44 are provided with cam faces 49 for cooperating with the shoulder 48. When the drill is raised to recover the core C the engagement of the spring urged dogs 43 and 44 tends to hold the ring 38 against movement so that the shoulder 48 is moved upwardly into camming engagement with the cam faces 49. This cooperation of the shoulder 48 with the faces 49 pivots the active ends of the dogs 43 and 44 downwardly and inwardly so that the dogs bite into the core. When the dogs 43 and 44 are in their fully actuated position they are effectively supported by the lower walls of the openings 41 to dependably retain and support the core C.

The core catching unit 13 is effective in breaking free hard cores from the formation and is effective in retaining hard cores. The unit 13 is arranged in the opening 21 at a point spaced above the unit 12. The core catching unit 13 includes a body member 50 movable along the wall of the opening 21. The lower portion of the collar 19 is internally recessed so that its opening forms a continuation of the opening 21 and the collar 19 has an internal downwardly facing shoulder 51 for limiting the upward movement of the core catcher body 50. The lower portion of the opening 21 has a downwardly and inwardly inclined wall 52. The lower portion of the core catcher body 50 has a downwardly and inwardly tapered exterior provided with circumferentially spaced slots or notches 53.

Elongate spring members or flexible members 54 project from the upper and lower ends of the body 50 at circumferentially spaced points. A ring 55 surrounds the upper portion of the body 50 and rivets 56 extend through openings in the ring 55, flexible members 54 and the body 50 to attach the flexible members to the body. Core gripping slips 57 are attached to the lower ends of

the flexible members 54 below the lower end of the body 50. The slips 57 have inclined outer surfaces for cooperating with the inclined wall 52. The inner sides of the slips 57 are toothed to effectively grip the core C. The notches 53 allow the required inward flexing of the members 54 and prevent sand from accumulating between the flexible members and body 50.

The end portions of the flexible members 54 projecting upwardly from the core catcher body 50 are curved or bent inwardly to engage the core C. The projecting upper end portions of the flexible members 54 are each bifurcated or longitudinally split into two branches or arms 58. The upper ends of the arms 58 are pointed to bite into the core. The projecting upper ends of the flexible members 54 in being longitudinally split are more flexible so that they do not injure the core during the drilling operation. The engagement of the projecting upper ends of the flexible members 54 with the core C tends to hold the core catcher 13 against movement and when the drill is raised to recover the core of the core catcher 13 tends to remain stationary so that the inclined wall 52 cooperates with the slips 57 to force them into tight gripping engagement with the core C.

The invention includes a dummy 60 for occupying the lower portion of the socket 29 when the drill is to be run or operated without the lower core catching unit 12. The dummy 60 is in the nature of a ring having substantially the same general configuration as the ring 38. When positioned in the open lower end of the socket 29 the dummy 60 prevents the upper end of the core from fouling or striking the shoulder 30. A dummy 61 is provided to replace the upper core catching unit 13 when the tool is to be operated without the unit 13. The dummy 61 is a tubular member having its lower external surface inclined to seat on the tapered wall 52. When the dummy 61 is in position in the opening 21 it centrally guides the core C and prevents the upper end of the core from engaging the shoulder 51.

The drill is operated in the well bore in the usual manner so that the cutters A and B make an annular cut in the earth formation and form the core C. The core C is received by the opening 31 and passes through the opening 21 into the inner barrel 18. When the drill is rotating during drilling the dogs 43 and 44 may engage the core to hold the ring 38 against turning and to hold the ring against the shoulder 30. The upper projecting ends of the flexible members 54 contact the core C during drilling to hold the core catcher body 50 against movement and in an up position where its upper end engages the shoulder 51. After a core of sufficient length has been formed the drill is raised to break the core free from the formation. When the drill is raised the spring urged dogs 43 and 44 engage the core C to tend to hold the ring 38 against movement so that the cam shoulder 48 moves upwardly against the cam faces 49 to positively pivot the dogs into the core. The long dogs 43 are adapted to penetrate soft cores and to move under shattered or broken cores. The shorter dogs 44 are adapted to bite into full sized cores and medium hard cores to break them free from the formation. When the dogs 43 and 44 are in their projected or actuated position they are effective in supporting or retaining the core when the drill is being withdrawn from the well.

The upper projecting ends of the flexible members 54 contact the core to hold the core catcher body 50 against movement when the drill is

raised so that the inclined wall 52 moves against the outer sides of the slips 57 to force the slips inwardly. The slips 57 are positively actuated to firmly grip hard cores and medium hard cores. The gripping engagement of the slips 57 with the core is such that the core is readily broken free from the formation. The core catching unit 13 is operable to recover and retain hard cores that might slip through the lower core catching unit 12. The core drill of the present invention having the two core catching units 12 and 13 is operable to recover cores of various characters and hard full sized cores as well as soft and undersized cores. The dummies 60 and 61 may be used when the drill is to be run with only one core catcher. The dummies 60 and 61 are simple, inexpensive members that may be readily arranged in the positions normally occupied by the core catchers.

Having described only a typical preferred form and application of our invention, we do not wish to be limited or restricted to the specific details set forth, but wish to reserve to ourselves any changes or variations that may appear to those skilled in the art or fall within the scope of the following claims.

Having described our invention, we claim:

1. In a core drill, a tubular body, a cutting head on the lower end of the body, a core catcher in the head embodying core engaging dogs, and a core catcher in the body embodying core engaging slips.

2. In a core drill, a tubular body, a cutting head on the lower end of the body, a floating ring in the head, pivoted core engaging dogs on the ring, a floating tubular member in the body above the ring, and core gripping slips carried by the member.

3. In a core drill, a tubular body, a tubular cutting head on the lower end of the body having an internal recess, a ring rotatable in the recess, pivoted core retaining dogs on the ring, and a core catcher in the body having core gripping slips.

4. A core drill, a tubular body having an inclined internal surface, a tubular cutting head on the lower end of the body having an internal shoulder, a tubular member freely arranged in the body, core gripping slips on the member actuated by cooperation with the said surface, a ring freely arranged in the head and core gripping dogs on the ring actuated by said shoulder.

5. In a core drill, a tubular body, a tubular cutting head on the lower end of the body having an internal recess, a ring rotatable in the recess, pivoted core retaining dogs on the ring, the dogs being of different lengths, and a core catcher in the body having core gripping slips.

6. A core drill, a tubular body having an inclined internal surface, a tubular cutting head on the lower end of the body having an internal shoulder, a tubular member freely arranged in the body, core gripping slips on the member actuated by cooperation with the said surface, a ring freely arranged in the head, pivoted core gripping dogs on the ring, and cam parts on the dogs adapted to cooperate with the shoulder to actuate the dogs.

7. In a core drill, a cutter head having a socket in its upper end, a tubular body member threaded in the socket so that its lower end forms a shoulder, a ring shiftable in the socket below the shoulder, pivoted core gripping dogs on the ring, a tubular part shiftable in the body member, and core gripping slips carried by the tubular part

actuated by engagement with the wall of the body member.

8. In a core drill, a tubular body having an inclined internal surface, a tubular cutter head having a socket into which the lower end of the body is threaded, a tubular member shiftable in the body, flexible members on the member having projecting upper ends for engaging the core, slips on the lower ends of the flexible members actuated to grip the core by cooperating with said surface, a ring shiftable and rotatable in the socket, the lower end of the body limiting the upward movement of the ring, and pivoted core gripping dogs on the ring actuated by relative longitudinal movement between the head and ring.

9. A core drill including a tubular body, an inner barrel rotatably supported at its lower end

in the body, the lower end of the inner barrel forming a downwardly facing internal shoulder in the body, a tapered surface on the interior of the body below said shoulder, a member shiftable and rotatable in the body below said shoulder, the shoulder limiting the longitudinal movement of the member, core gripping slips carried by the member and actuated by said surface upon longitudinal movement of the body, a cutter head threaded on the body and having an internal 10 recess, the lower end of the body forming the upper wall of the recess, a ring rotatable and shiftable in the recess, and pivoted core gripping dogs on the ring actuated by longitudinal movement of the body.
